UNITED STATES PATENT OFFICE

96,492

DESIGN FOR A GAME BOARD OR SIMILAR ARTICLE

Cecil C. Lutes, Bellingham, Wash.

Application December 1, 1934, Serial No. 54,217

Term of patent 14 years

To all whom it may concern:

Be it known that I, Cecil C. Lutes, a citizen of the United States, residing in Bellingham, in the county of Whatcom and State of Washington, have invented a new, original, and ornamental Design for a Game Board or Similar Article, of which the following is a specification, reference being had to the accompanying drawing, forming part thereof, in which Figure 1 is a plan view of the game board or similar article, showing my new design. The shading of the various squares is for the purpose of designating contrast of color

and not indicating any particular color designations.

Figure 2 is an edge elevation of the game board.

I claim:—

The ornamental design for a game board, or similar article, as shown and described.

Signed at Bellingham, in the county of Whatcom, and State of Washington, this 24th day of November, 1934.

CECIL C. LUTES.
